DESIGN FOR A TOWEL RACK

Roy S. Sanford, Oakville, Conn., assignor to The Autoyre Company, Incorporated, Oakville,
Conn., a corporation of Connecticut

Application August 1, 1941, Serial No. 102,627

Term of patent 7 years

To all whom it may concern:

Be it known that I, Roy S. Sanford, a citizen of the United States, residing at Oakville, in the county of Litchfield and State of Connecticut, have invented a new, original, and ornamental Design for a Towel Rack, of which the following is a specification, reference being had to the accompanying drawing, forming a part thereof.

Fig. 2 is a front elevational view of the towel rack shown in Fig. 1; and

Fig. 3 is a side elevational view of the towel rack shown in Fig. 1.

I claim:

The ornamental design for a towel rack, substantially as shown.

ROY S. SANFORD.
